UNITED STATES PATENT OFFICE.

HERBERT W. CHRISTIAN, OF DETROIT, MICHIGAN.

ELECTRICALLY-CONTROLLED GAS WATER HEATER.

Application filed June 30, 1923. Serial No. 648,856.

To all whom it may concern:

Be it known that I, HERBERT W. CHRISTIAN, a citizen of the United States of America, residing at Detroit, in the county of Wayne and State of Michigan, have invented certain new and useful Improvements in Electrically-Controlled Gas Water Heaters, of which the following is a specification, reference being had therein to the accompanying drawings.

A simple form of gas operated water heater includes a tank or boiler serving as a reservoir and communicating with the boiler is a coil of tubing enclosed in a casing supported at the side of the boiler with a gas burner in the bottom of the casing adapted to heat the coil of tubing and the water therein. Such a heating apparatus is ordinarily located in the basement of a house or in the kitchen and if the apparatus is to be placed in operation it is necessary that the gas be turned on and ignited. If hot water is required in a second story bath room a housewife may have to travel to the kitchen or basement to place the apparatus in operation, and in many instances a trip must be made from the kitchen to the basement. To still utilize the simple form of gas operated water heater outlined above and yet permit of a housewife placing the apparatus in operation from a bath room, kitchen or from any other point about a house, I have devised an electrically operated controlling device which may be easily and quickly installed without any material change or modification in an ordinary gas operated water heater.

The electrically controlled device necessarily includes a gas valve and I utilize a magnet to open the valve and depend upon gravity means and gas pressure to close the valve. The magnet is placed in circuit with the thermostat located on the boiler and it is by virtue of this thermostat that the controlling device is automatically operated to cause a cessation in the operation of the water heater after the water has reached a predetermined temperature at a desired point within the boiler, such point insuring a sufficient quantity of hot water for a bath or other purposes.

My controlling device also includes novel means to prevent a thermostat from arcing or chattering, so that the operation of the controlling device will be noiseless, safe, and serviceable.

My invention will be hereinafter described by aid of the drawing, wherein—

Figure 1 is a side elevation of a gas operated water heating apparatus provided with an electrical control device in accordance with my invention;

Fig. 2 is an enlarged elevation of a portion of the device;

Fig. 3 is a vertical sectional view of the electrically controlled device, showing it supported from the side of a boiler, and

Fig. 4 is a horizontal sectional view taken on the line IV—IV of Fig. 3.

In the drawing, the reference numeral 1 denotes a stand or support 1 having a side extension 2 and on the stand is a tank or boiler 3 having pipe connections 4 for the circulation of water through said boiler.

On the side extension 2 is a casing 5 containing a coil of tubing 6 with the end convolutions of the tubing connected to the boiler 3 so that water may circulate through the tubing. At the bottom of the casing 5 is a gas burner 7 having a gas inlet pipe 8, and adjacent the burner 7 is the end of a gas supply pipe 9 adapted to maintain a pilot light to ignite gas emitted by the burner 7.

Attached to the boiler 3 or to a support in proximity thereto is a bracket 10. For the purpose of holding the bracket 10 relative to the boiler 3, said boiler may be provided with a band 11 having a socket 12 for a three-way connection 13 into which may be screwed a gas supply pipe 14 and a bracket pipe 15. The upper end of the pipe 8 may be attached to the bracket 10, below the pipe 15, and said pipes are adapted to support a valve structure or body 16 to the upper end of which may be connected a gas supply pipe 9 so as to receive a constant supply of gas from the pipe 14. In the valve body 16 is a valve seat 17 for a valve 18 controlling communication between the pipes 8 and 15.

The valve 18 has a valve rod 19 extending downwardly through the bottom of the valve body 16 and through an angular extension 20 of the bracket 10. On the angular extension 20 of said bracket is a magnet core or frame 21 provided with a magnetic coil 22, and on the lower end of the valve rod 19 is an armature 23 movable to and from the pole pieces of the magnetic core or frame 21. The armature 23 is movable between guides 24 of the frame 21 and said armature

is preferably in the form of a weight so that it may cooperate with the pressure of gas in the upper part of the valve body 16 in holding the valve 18 normally seated and closed.

On the bracket 10 above the valve body 16 is a casing 25 containing a support 26 made of insulation material. On the support 26 are binding posts 27 to 32 inclusive and a 10 thermostatic device 33 which has one end thereof fixed to the support 26 and connected, as at 34 to the binding posts 27 and 29. This thermostatic device is composed of a thermostatic strip capable of flexure by 15 heat, and wound on the strip is a shunt coil of high resistance, serving two purposes. First that of preventing arcing and vibrating of the thermostatic device 50 to be herein-after considered, and second, heating the 20 thermostatic strip to cause it to be flexed and moved to and from the contact member 35 mounted on the support 26, said contact member having a set screw 36 to limit the movement of the thermostatic device 33. At 25 attached to the contact member 35 is a resilient contact arm 37 adapted to engage binding post 31 and said contact arm is adapted to be raised into engagement with the binding post 31 by an insulator 38 on the upper 30 end of a rod 39 attached to an adjustable sleeve 40 carried by the valve rod 19.

At some point remote from the bracket 10 there may be a switch 41 having leading-in wires 42 from a suitable 35 source of electrical energy, and said switch is connected by wires 43 and 44 to the binding posts 30 and 29 respectively. The binding post 30 is connected by a wire 45 to the binding post 40 32 and said binding post by a wire 46 to the magnetic coil 22, which in turn is connected by a wire 47 to the binding post 31. Another wire 48 connects the binding posts 28 and 31.

45 Suitably mounted on the side of the boiler 3 is a casing 49 for the thermostatic device 50 under the influence of water temperatures in the boiler 3 or a chamber within the casing 49 which communicates with the boiler 3. The casing 49 has a contact member 51 connected by a wire 52 to the binding post 28 and said contact member 51 is adjustable relative to the free end of the thermostatic device 50. This thermostatic device 55 is connected by a wire 53 to another thermostatic device 54 located within the casing 5 adjacent the pilot light, and said thermostatic device is connected by a wire 55 to the binding post 27. The thermostatic device 60 50 may be a conventional form of electric switch having a contact member adapted to be flexed by heat. As long as the pilot light burns the thermostatic device 54 completes a circuit for the wires 53 and 55, but 65 should the pilot light be extinguished the

thermostatic device 54 opens the circuit and renders the entire controlling device temporarily inoperative.

Assuming that water is to be heated in the coil of tubing 6 and the boiler 3, the switch 70 41 is turned on and the following circuit completed:—Wires 43 and 45 to the binding post 32, wire 46 to the magnetic coil 22, wires 47 and 48 to the binding post 28, by wire 52 to the thermostatic device 50, by 75 wire 53 to the thermostatic device 54, by wire 55 to the binding post 27, and connection 34, binding post 29 and wire 44 to the switch 41. This closed circuit causes the magnetic coil 22 to be energized whereby the 80 armature 23 is raised carrying with it the valve rod 19 and the insulator rod 39. Unseating of the valve 18 allows gas to be supplied to the burner 7 and be ignited by the pilot light, so that water within the coil 6 85 will be heated.

Simultaneous with the opening of the gas valve the resilient arm 37 is raised into engagement with the contact post 31, thus placing the thermostatic device 33 in parallel 90 with the thermostat 50, but since the device 33 is of high resistance it serves as a shunt coil to prevent arcing during the operation of the thermostatic device 50 to open the circuit at the contact member 51 due to the 95 temperature of water within the boiler 3 or the casing 49. On account of the temperature of the water in the boiler 3 being gradually raised and the thermostatic device 50 gradually operating, there might be arcing of the thermostatic device 50 if it were not for the thermostatic device 33. Operation of the thermostatic device 50 leaves the thermostatic device 33 in circuit and as the coil is heated the strip is flexed to open the 105 circuit, deenergize the magnet and cause the gas to be shut off.

Assuming that a predetermined quantity of water has been heated and the thermostatic device 50 flexed to break the circuit at 110 the contact member 51, the magnetic coil 22 is no longer energized and the armature 23 descends by gravity closing the gas valve 18 which cuts off the supply of heat to the coil of tubing 6 constituting a conventional 115 form of gas heater. Closing of the valve 18 lowers the rod 39 and the arm 37 breaks the circuit for the thermostatic device 33.

During the heating of the water the switch 41 can be turned off at any time, but 120 should it be left on then the thermostatic device 50 will automatically control the heating of the water. If previously heated water is permitted to cool off in the boiler 3, the thermostatic device 50 will eventually 125 close the circuit and again start the heater, and such is the operation of my device as long as the switch 41 is turned on. Of course, at night when no hot water is to be used the switch 41 will be turned off, but 130

during the day it may be left on so that there will be a constant supply of hot water in the boiler 3.

Should the pressure of gas be so low that it will not maintain a pilot light the thermostatic device 54 maintains the circuit open and consequently the valve 18 is closed. This is a safety factor that precludes the escape of gas into a compartment in which 10 the gas heater is located.

I attach considerable importance to the fact that my electrical control device is applicable to an ordinary gas operated water heater, and while in the drawing there is 15 illustrated a preferred embodiment of my invention, it is to be understood that the structural elements are susceptible to such variations and modifications as fall within the scope of the appended claims.

20 What I claim is:—

1. The combination of a boiler, a water heater communication therewith, a gas burner for said water heater, an electrically operated gas valve adapted to supply gas 25 for said gas burner, a switch controlled operating circuit for said electrically operated gas valve, a thermostatic switch carried by said boiler in the operating circuit of said gas valve so that the temperature of 30 water in said boiler may control the turning off of the gas, and a thermostatic device in said operating circuit serving as a shunt during the operation of the thermostatic

switch to prevent arcing of said switch, said thermostatic device being operative to 35 open the circuit of said electrically operated gas valve so that said valve may close.

2. The combination claimed in claim 1, wherein said electrically operated gas valve is of the magnetic type for valve opening 40 purposes, with a portion of the magnet designed to close the gas valve by gravity.

3. The combination claimed in claim 1, wherein said electrically operated gas valve, includes means for shunting the operating 45 circuit through said thermostatic device.

4. The combination claimed in claim 1, wherein said electrically operated gas valve includes a magnet having an armature serving as a weight adapted to close said 50 valve when said magnet is de-energized.

5. In a water heating apparatus wherein a thermostatic switch is in an electric controlling circuit of the apparatus, and a valve is controlled by the circuit, means to prevent 55 arcing of said thermostatic switch, said means including a thermostatic device placed in a shunt circuit by operation of said valve to prevent arcing of said thermostatic switch, said thermostatic device being operable to break the shunt circuit 60 after the operation of said thermostatic switch.

In testimony whereof I affix my signature.

HERBERT W. CHRISTIAN.
